METER BOX COVER

Frank M. Brooks, San Marino, Calif.; Harry H. Lehman, executor of said Frank M. Brooks, deceased

Application November 27, 1953, Serial No. 394,600

1 Claim. (Cl. 220—31)

This invention relates to a cover for concrete water meter boxes.

Such boxes are now in common use, and are provided with metal or concrete covers. A lid hinged on the cover may be lifted when it is desired to read the meter.

It is one of the objects of this invention to provide a cover of this type, of improved and simplified construction.

It is another object of this invention to make it possible to provide a lid structure such that the view of the meter reader is not materially obstructed by the hinge parts when the lid is opened.

This invention possesses many other advantages, and has other objects which may be made more clearly apparent from a consideration of one embodiment of the invention. For this purpose, there is shown a form in the drawings accompanying and forming part of the present specification. This form will now be described in detail; but it is to be understood that this detailed description is not to be taken in a limiting sense, since the scope of this invention is best defined by the appended claim.

Referring to the drawings:

Figure 1 is a top plan view of a meter box in which the invention is embodied;

Fig. 2 is a sectional view taken along a plane corresponding to line 2—2 of Fig. 1;

Fig. 3 is a fragmentary view, similar to Fig. 2, showing the lid for the viewing aperture in the open position; and

Fig. 4 is an enlarged sectional view taken along a plane corresponding to line 4—4 of Fig. 3.

The meter box 1 is shown in this instance as of general rectangular configuration and having an open top. It may conveniently be made of concrete or cement or other non-metallic plastic material. It is intended to be disposed over a water meter and in such position that its top will form a substantially flush surface.

The opening in the top of box 1 is formed by walls 2 leading to a flange 3. The top surface 4 of the flange 3 is substantially horizontal and forms a shoulder below the top surface 5 of the box. This shoulder is substantially horizontal and forms a support for a cover member 6.

This cover member may also be made of non-metallic such as concrete or cement. This cover member may have a depending portion 7 which extends below the shoulder 4.

The cover member 6 is provided with a viewing aper-

2

ture 8 adapted to be closed by a lid 9. When the lid 9 is held in the open position of Fig. 3, a meter reader may inspect the meter within the box.

The lid 9 may be made of ribbed cast iron or the like, having depending hinge lugs 10 at opposite edges thereof. The outer surfaces of these hinge lugs are flush with the corresponding edges of the lid 9. A reinforcing rib 11 is formed at the inner surface of each of the lugs 10.

For pivoting the lid 9, use is made of a pin 12. This pin 12 extends through both of the hinge lugs 10 and is accommodated in a cored hole 13 in the cover 6. This cored hole, as shown most clearly in Fig. 1, does not extend entirely through the cover 6. The pin 12 can be inserted in the cored hole and it can be prevented from accidental removal by a filling of plastic material below the pin 12, as viewed in Fig. 1.

The lid 9 is provided with an opening 14 for the insertion of an appropriate tool or hook for lifting the lid to the position of Fig. 3. Furthermore, the right hand edge of the lid 9 may rest upon a horizontal shoulder 15 formed along one edge of the viewing aperture 8.

In order to limit the opening movement of the lid 9 so that, when released, it will fall by gravity to the closed position, a stop is provided. For this purpose, there are bosses 16 at opposite edges of the aperture 8. These bosses are formed integrally with the cover 6. They provide an upper shoulder 17 also serving to limit the closing movement of the lid 9. A stopping surface 18 is provided on the boss 16 adapted to cooperate with a corresponding stopping surface 19 of each of the hinge lugs 10.

The cooperating stopping surfaces 18 and 19 are so arranged that no portion of the elements forming these stopping surfaces extend above the surface of the lid 9 when the lid is in the closed position of Fig. 2.

The inventor claims:

In a cover structure for a meter box or the like: a cover having a viewing aperture; a metal lid for the aperture, adapted to lie substantially flush with the cover member; said lid having a pair of depending hinge lugs at opposite edges of the lid; and a hinge pin extending through both of the lugs, and having ends entirely supported in recesses in the cover; said lugs having surfaces flush with said edges and adjacent opposite edges of the viewing aperture; said opposite edges of the aperture having integrally formed bosses forming shoulders cooperating with the stop surfaces formed on the lugs for limiting the opening movement of the lid; said bosses and the hinges being below the top surface of the cover when the lid is closed; the top edges of the bosses serving to limit the closing movement of the lid.
